I. M. PEASE

TRUSS PAD

Filed April 19, 1922

I.M. Pease, Inventor

By *Chasnow & Co.*
Attorney

UNITED STATES PATENT OFFICE.

ISAAC M. PEASE, OF CINCINNATI, OHIO.

TRUSS PAD.

Application filed April 19, 1922. Serial No. 555,550.

To all whom it may concern:

Be it known that I, ISAAC M. PEASE, a citizen of the United States, residing at Cincinnati, in the county of Hamilton and State of Ohio, have invented a new and useful Truss Pad, of which the following is a specification.

This invention aims to provide novel means for moving a truss pad inwardly or outwardly with respect to the body of the wearer, it being possible to swing the pad about an axis, and to move the pad longitudinally of a support, the aforesaid adjustments being independent of each other and enabling the operator to arrange the pad properly to accommodate the widely different conditions existing with respect to ruptures.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a device constructed in accordance with the invention; Figure 2 is a section on the line 2—2 of Figure 1; Figure 3 is an end elevation showing the button on the post; Figure 4 is an elevation showing a portion of the support.

In carrying out the invention, there is provided a pad including a body 1. The body of the pad may be made in various ways, but, as shown, the body of the pad includes an outer plate 2 and an inner plate 3 connected by clamping screws 4. The cushion 5 may be of any desired sort, but, by way of illustration, merely, the cushion is shown as including a casing 6, having its edge bound between the plates 2 and 3, a stuffing 7 being located within the cushion.

A socket 8 is secured to the outer plate 2 and extends through the inner plate 3, the socket having an external head 9 located in an enlarged seat 10 formed in the outer

plate 2. A set screw or like clamping device 55 11 is mounted in the head 9 of the socket 8. A channel 12 is formed in the plate 2 transversely thereof, as shown in Figure 1, the channel communicating with the seat 10 and being alined with the set screw 11, the purpose of the channel being to permit a screw driver to be applied readily to the screw 11.

The numeral 14 marks a post, threaded for adjustment in the socket 8 and into the head 9 thereof. A projection 15 extends 65 from the post 14 between the convolutions of the thread on the post and is located adjacent to the inner end of the post, the projection 15 being adapted to cooperate with the thread in the socket 8, to prevent the 70 post from being threaded accidentally, out of the socket, thereby bringing about a detachment of the pad from the post. At its outer end, the post 14 is provided with an enlarged button 16 having radial ribs 17. 75

A screw 18 or like clamping device is threaded into the outer end of the post 14 and has an enlarged head 19, a loop-shaped handle 20 being pivoted at 21 to the head 19 of the screw 18, it being possible to turn the 80 handle 20 into alinement with the axis of the screw 18, when it is desired to rotate the screw, the handle being turned at right angles to the axis of the screw when not in use, as shown in Figure 2.

The numeral 22 marks a support of any desired sort, provided adjacent to one end with an elongated slot 23. The support 22 has ribs 24 located adjacent to the slot.

The screw 18 passes through the slot 23 90 of the support 22, the support being bound between the head 19 of the screw and the button 16 on the post 14. By loosening the screw 18, the truss pad may be turned to any desired position about an axis represented by the screw. Further when the screw 18 is loosened, the pad may be shifted longitudinally of the support 21, the screw moving in the slot 23. When the head 19 of the screw 18 is seated against the support 21, the ribs 24 on the support coact with the ribs 17 on the button 16 of the post 14, to hold the pad on the support 21 in any position to which the pad may have been adjusted.

The post 14 may be threaded inwardly or outwardly in the socket 8, thereby to vary the pressure afforded by the pad on the

rupture and when the post has been adjusted as aforesaid, the post and the pad may be held against relative movement by advancing the set screw 11 until the same engages the post.

It is to be observed that the device comprises means whereby several independent adjustments may be secured. Thus, the pressure may be increased by advancing the pad through the instrumentality of the post 14 which is threaded into the socket 8. The pad may be shifted along the support 21 longitudinally thereof, owing to the presence of the slot 23 which receives the screw 18. Further, the pad may be swung pivotally on an axis represented by the axis of the screw 18.

As a result of the foregoing, one single form of the device is adapted to be used in connection with ruptures of different sorts, and, owing to the many adjustments which are possible, the device may be made to accommodate itself to all of the complex conditions existing in connection with ruptures.

What is claimed is:—

A device of the class described comprising a pad, a socket carried by the pad, a post threaded into the socket, holding means carried by the outer end of the post, a support retained by the holding means on the outer end of the post, and a set screw threaded into the side of the socket and engaging the post to hold the post against rotation, the pad having a seat wherein the outer end of the socket is housed, thereby to permit the support to be brought up close to the pad, the pad having a lateral channel wherein the set screw is located, thereby rendering the screw accessible notwithstanding the fact that the outer end of the socket is located in the seat.

In testimony that I claim the foregoing as my own, I have hereto affixed my signature in the presence of two witnesses.

ISAAC M. PEASE.
